Frank S. Jones

UNITED STATES PATENT OFFICE.

FRANK S. JONES, OF PHILADELPHIA, PENNSYLVANIA.

STRAIGHTENING PRESS.

Application filed May 1, 1920. Serial No. 378,145.

To all whom it may concern:

Be it known that I, FRANK S. JONES, a citizen of the United States, residing at Philadelphia, in the county of Philadelphia and State of Pennsylvania, have invented certain new and useful Improvements in Straightening Presses, of which the following is a specification.

Prior to my present invention it was usually the custom in straightening axles, shafts or other elongated articles, to place the article to be straightened in the press and, after operating the press, to remove the article to a lathe or other centering means whereby the article could be supported and rotated in order to test the result of the pressing. Certain machines have been invented, however, where provision was made on the press for supporting the article after having been engaged by the pressure screw in order to test the result of the straightening but in these latter mentioned machines the supporting means for testing the true-ness of the article were in such position that unless they were entirely removed from the machine they would interfere with the proper manipulation of the article during the pressing action.

One object of my invention is to provide a straightening press which will include means readily adapted for testing the result of the pressing action without requiring that the article be removed from the press or its general position relatively to the pressure screw and at the same time to so construct the supporting or testing means that it can be quickly and easily moved into such position as not to interfere with the proper manipulation of the article to the straightened during the pressing action.

A further object is to make my invention of a durable and comparatively simple construction.

These objects, and other advantageous ends which will be described hereinafter, I attain in the following manner, reference being had to the accompanying drawings in which

Figure 1 is a side elevation of my improved straightening press.

Figure 2 is a fragmentary section showing certain features of my invention.

Figure 3 is an end elevation of the press shown in Figure 1 looking in the direction of the arrow *a* in Figure 1.

55

Figure 4 is an enlarged fragmentary section taken on the line 4-4 of Figure 1, and

Figure 5 is a view of similar character to Figure 4 showing certain of the parts moved into other positions such for example as those occupied during the pressing operation of an article which is to be straightened.

Referring to the drawings, 6 represents a heavy metallic base which is mounted on wheels 7 so that it may be easily rolled around on a floor and this base has a groove 8 providing a guideway for V-blocks 9 in which the article, such for example as the axle 10 which is to be straightened, is positioned. The base 6 has four studs 11 secured thereto which project above the top thereof; said studs serving to support a head 12 having a pressure screw 13 therein adapted when turned to engage the article 10 between the blocks 9 for straightening purposes. A shaft 14 has a bearing in the base 6 and projects beyond the opposite ends thereof. This shaft has a key way 15 cut longitudinally therein into which project keys 16 in centering arms 17; said keys 16 having end portions embracing opposite faces of said centering arms to retain the keys to the arms. The shaft 14 extends through the arms 17 and forms a support for said arms as clearly shown in Figure 1; the arms being located adjacent opposite ends of the shaft 14. Set screws 18 extend through each of the arms 17 and are operative to jam the keys 16 into locking engagement with the shaft 14; said set screws being provided

70

with hand wheels 19 to facilitate their action. However, it will be noted that when the set or clamping screws 18 are loosened the arms are free to slide lengthwise on the shaft 14. Centers 20 have screw threaded portions 21 in screw threaded engagement with the arms 17 at positions remote from the shaft 14; said portions 21 having hand wheels 22 thereon whereby the centers can be moved in directions parallel with the shaft 14 for

85

100

95

100

engaging the ends of the article 10 after the latter has been pressed; it being necessary to slightly lift the article 10 out of the blocks 9 into alignment with the centers 20 as 5 shown in Figure 1 so that by turning up on the screw threaded portions 21, the ends of the centers will engage the opposite ends of the article 10 and permit the latter to be rotated in order to test the trueness of the 10 straightening action.

The shaft 14 is freely rockable in the base 6 and said shaft 14 has a collar 23 secured thereto adjacent one end of the base 6; said collar having lugs 24 and 25 projecting 15 therefrom as clearly shown in Figures 4 and 5. The base 6 has a stop pin 26 projecting therefrom and located between the lugs 24 and 25. A latch 27 is pivoted at 28 to the base 6 and has a detent portion 29 and a 20 handle 30 projecting therefrom. When an article, such for example as the article 10, is in position upon the blocks 9 during the straightening action. The centering arms 17 are in the position shown in dot-and-dash 25 lines in Figure 5 and are held in this position due to the engagement of the lug 24 with the stop pin 26. In this manner the centering arms are in a position entirely below the article 10 so that the latter may be 30 moved lengthwise without interference. After the straightening action has taken place the arms 17 can be swung into an upright position as shown in Figures 1, 3 and 4, and the centers, after the article 10 has been raised 35 from engagement with the blocks 9, can be moved into supporting engagement with the ends of the article 10 to permit the latter to be rotated to test the result of the straightening action; it being noted that since the 40 centering arms are secured to the shaft 14 that the entire shaft 14 will rock or partially rotate in the base 6 and the detent portion 29 of the latch 27 can be swung into engagement with the lug 25 so as to confine the 45 latter between said detent portion and the stop pin 26. Thus the centering arms 17 and centers can be swung into operative position to support the article which has been pressed, without entirely removing said article from 50 the machine and thus the straightening of the article is facilitated and the operation can be done conveniently.

While I have described my invention as taking a particular form, it will be understood 55 that the various parts of my invention may be changed without departing from the spirit thereof, and hence I do not limit myself to the precise construction set forth, but consider that I am at liberty to make such 60 changes and alterations as fairly come within the scope of the appended claims.

Having thus described my invention, what I claim as new and desire to secure by Letters Patent is:—

65 1. A straightening press including a base,

straightening means, aligned blocks for supporting an article to be straightened, a shaft rockably mounted upon the base under, and in the same vertical plane with, the centers of the supporting blocks, arms slidably 70 mounted upon the rock shaft and adapted to be moved to extend vertically above said shaft, means for locking the arms in their vertical position and centering members carried by the arms and movable into position 75 to support the article above the supporting blocks, substantially as described.

2. A straightening press including a base having portions forming a seat for an article to be straightened; a shaft rockably mounted in said base and having portions projecting beyond the opposite ends thereof; centering arms secured to said shaft; centers on 80 said arms located at positions remote from said shaft and adapted to be moved into a vertical plane above said seat; straightening means; and means for locking said shaft to the base whereby an article which is to be straightened can be supported by said centers in said position above said seat; substantially as described.

3. A straightening press including supporting means for an article to be straightened; pressing means for engagement with said article while on said supporting means; supporting arms having centering portions movable into position to support said article between said supporting means and said straightening means; means for limiting the movement of said arms when said position is reached; and means for locking said arms in said position; substantially as described.

4. A straightening press including a base; a shaft rockably mounted in said base and having portions projecting beyond the opposite ends thereof; centering arms secured to said shaft; centers on said arms located at positions remote from said shaft; straightening means; a latch for locking said shaft to the base whereby an article to be tested can be supported by said centers, said latch being releasable to permit said shaft to be rotated to swing said arms and centers into a position out of alignment with said article; and means for limiting the movement of said shaft during said latter mentioned rotation; substantially as described.

5. A straightening press including a base; a shaft rockably mounted in said base and having portions projecting beyond the opposite ends thereof; centering arms secured to said shaft; centers on said arms located at positions remote from said shaft; straightening means; lugs secured relative to said shaft and spaced apart; a stop on said base projecting between said lugs; and a latch movably secured to said base and movable into a position to lock one of said lugs between it and the stop whereby the centering 120 125 130

arms and centers will be locked in a position so that the latter can be used as a support for an article to be tested, said shaft being rotatable to swing said arms into a position 5 in which their centers are out of alignment with said article, said other stop serving to limit said latter movement by engaging said stop; substantially as described.

In testimony whereof I have signed my name to this specification in the presence of 10 two subscribing witnesses.

FRANK S. JONES.
